Primary Examiner — Elizabeth Albert*Assistant Examiner* — Kelley Donnelly(74) *Attorney, Agent, or Firm* — Cislo & Thomas, LLP(57) **CLAIM**

I claim the ornamental design for a china cabinet/buffet, as shown and described.

DESCRIPTION

FIG. 1 is a perspective view of my china cabinet/buffet;

FIG. 2 is a front view thereof;

FIG. 3 is a right side view thereof;

FIG. 4 is a left side view thereof;

FIG. 5 is a top view thereof;

FIG. 6 is a close-up view of a portion of the narrow, horizontal band of ornamentation above the four upper doors of my china cabinet/buffet;

FIG. 7 is a close-up view of a portion of the drawers of my china cabinet/buffet; and,

FIG. 8 is a close-up view of the lower central doors of my china cabinet/buffet.

The broken lines are for environmental purposes only and form no part of the claimed design.
